UNITED STATES PATENT OFFICE.

BENJAMIN LIPPER, OF PHILADELPHIA, PENNSYLVANIA, ASSIGNOR TO HIMSELF, AUGUSTUS A. LAZARUS, AND ISAAC A. SCHWARZ, OF SAME PLACE.

DESIGN FOR TRIMMING.

SPECIFICATION forming part of Design No. 23,978, dated January 29, 1895.

Application filed December 28, 1894. Serial No. 533,228. Term of patent 3½ years.

To all whom it may concern:

Be it known that I, BENJAMIN LIPPER, a citizen of the United States, residing in Philadelphia, Pennsylvania, have invented a certain new and original Design for Trimming, of which the following is a specification.

My design for trimming is fully shown in the accompanying drawing which represents an enlarged face view of a piece of the trimming.

The design comprises the central band *a*, opposite side bands *b*, projecting edge loops *l* and links *f*. These links *f* lie above the

side bands *b* and edge loops *d*, and the adjoining ends of the links pass under raised portions of the central band *a*. 15

I claim—

The design for trimming substantially as described and shown.

In testimony whereof I have signed my name to this specification in the presence of two subscribing witnesses.

BENJAMIN LIPPER.
